B. P. HANSON.
NECK YOKE.
APPLICATION FILED DEC. 15, 1913.

1,134,968.

Patented Apr. 6, 1915.

UNITED STATES PATENT OFFICE.

BENNIE P. HANSON, OF MONTICELLO, IOWA, ASSIGNOR OF ONE-HALF TO LONE GRENARD, OF BANCROFT, IOWA.

NECK-YOKE.

1,134,968.

Specification of Letters Patent.

Patented Apr. 6, 1915.

Application filed December 15, 1913. Serial No. 806,842.

To all whom it may concern:

Be it known that I, the undersigned, BENNIE P. HANSON, a citizen of the United States, residing at Monticello, in the county 5 of Jones and State of Iowa, have invented certain new and useful Improvements in Neck-Yokes; and I do hereby declare the following to be a full, clear, and exact description of the invention, such as will enable others skilled in the art to which it 10 pertains to make and use the same.

This invention relates to neck yokes and has for one of its objects the construction of a device combining lightness, rigidity, and 15 practically indestructible.

Another object of this invention is the provision of a neck yoke comprising parts thereof so constructed and arranged to most effectually resist any undue strain which 20 may be exerted thereupon.

A further object of this invention is to provide a neck yoke constructed, preferably of metal, and which is efficient, durable and which can be manufactured at a nominal 25 cost.

These and other objects will more fully appear and the nature of the invention, the construction, combination and arrangement of parts as described in the specification, 30 will be clearly understood as defined in the appended claim and illustrated in the accompanying drawings, in which,

Figure 1 is a perspective view of the invention showing the device in its complete 35 form ready for use. Fig. 2 is a front elevational view of the device shown in Fig. 1 with the exception that one of the parts has been removed to illustrate the assembling of the parts in the interior thereof. Fig. 3 is a 40 vertical transverse sectional view on the line 3—3 of Fig. 2 showing the mounting of the parts at the center of the device. Fig. 4 is a vertical sectional end elevation on line 4—4 of Fig. 2 which shows the arranging of 45 the loops at the ends of the device.

Like reference characters denote similar parts throughout the several views of the drawings and reference being had to the same, 1 denotes the neck yoke constructed 50 preferably of metal and 2 denotes two metal bars of rectangular form in cross section and at the center thereof and which bars are designed to be swaged or rounded toward the ends 3 thereof to assume a tubular form 55 at the ends thereof when the bars are joined

and which is adapted to receive the strap loops 15 to be hereinafter described. The bars 2 are positioned in parallel relation to each other with their concave portions adapted to face in contact with each other, at 60 the center of the bars 2 the same are spaced apart and between the bars and within the space therebetween is mounted an inverted U-shaped hanger which hanger is provided with the horizontal portion 4 and the depending side members 5 which side members 5 are each provided with a suitable aperture for the reception of the swivel bolt 7. The hanger is adapted to embrace the pair of rivets 6 and within the space between the 70 bars and which rivets are designed to retain the hanger and the bars 2 in rigidly secured relation.

Arranged upon the swivel bolt 7 of the hanger 4 is a tongue support 8 which support is formed by doubling the same upon itself and which is also adapted to surround the swivel bolt 7 as shown at 10 and which tongue support is securely held around the swivel bolt 7 by the circular metallic clamp 75 80 11 and which clamp plate is affixed to the tongue support through the medium of the rivets 12. The tongue supporting member is provided with enlarged apertures at the ends thereof which apertures are adapted to 85 register when the ends of the support are brought together after its attachment to the swivel bolt 7 thus providing for the registration of the apertures 9.

Arranged at each of the ends of the yoke 1 90 and between the meeting faces of the semi-circular ends 3 of the bars 2 are the strap loops 15 which loops are preferably square in shape and form and which loops 15 are adapted to embrace the pair of rivets 16 and 95 which rivets are adapted to hold the semi-circular ends of the bars 2 in rigidly secured position and to thus also maintain the strap loops 15 in secured position between the meeting faces of the ends 3, the ends 3 being provided with the recesses 13 in each of the meeting faces of the bars 2 at the ends 3 thereof and which recesses are adapted to 100 register with each other for permitting the side members of the strap loop 15 to pass 105 therebetween and to thus permit the meeting faces of the semi-circular ends 3 to lie flush with each other at their respective ends of the bars 2.

While I have described and illustrated the 110

2
preferred embodiment of my invention, I hereby reserve the right to make such alterations and variations therein as I may deem expedient and which will not depart from the spirit of this invention or conflict with the scope of the claim.

Having thus fully described my invention what I claim as new and desire to secure by Letters Patent is:

- 10 In a neck yoke comprising two bars, rectangular in form intermediate of their ends, said bars being swaged to form tubular ends terminating in a semi-circle, said bars being spaced apart at their rectangular portions
15 intermediate of their ends; an inverted U-shaped hanger mounted between the two bars at the center thereof; a swivel bolt con-

necting the two ends of the said hanger, a tongue support surrounding the said swivel bolt and depending therefrom, having an 20 aperture in the center thereof to receive the end of the tongue and a clamp plate surrounding the tongue support where said tongue support surrounds the said swivel bolt, and being securely riveted to the said 25 tongue support.

In testimony whereof I have signed my name to this specification in the presence of two subscribing witnesses.

BENNIE P. HANSON.

Witnesses:

GEO. L. LOVELL,
RUTH L. NELSON.
